UNITED STATES PATENT OFFICE.

ROBERT W. SCOTT, OF LEEDS POINT, NEW JERSEY, ASSIGNOR OF ONE-HALF TO LOUIS N. D. WILLIAMS, OF OGONTZ, PENNSYLVANIA.

RIB-KNITTED FABRIC.

No. 869,986.

Specification of Letters Patent.

Patented Nov. 5, 1907.

Application filed October 25, 1905. Serial No. 284,395.

To all whom it may concern:

Be it known that I, ROBERT W. SCOTT, a citizen of the United States, residing at Leeds Point, New Jersey, have invented certain Improvements in Rib-Knitted Fabrics, of which the following is a specification.

The object of my invention is to produce a rib knitted fabric having in one portion a greater number of wales than in the other, for instance, the fabric may be a tube having in one portion 160 or 180 wales and in the other 10 portion only 120 wales, or the fabric may have in the portion containing the greater number of wales a two-and-one rib or a two-and-two rib, and in the portion having the lesser number of wales a one-and-one rib.

The fabric is such that it can be readily produced 15 upon a circular knitting machine, change in the character of the web being effected by manipulation of the needles of the machine and without stopping said machine or requiring the intervention of an attendant, the invention being therefore especially adapted for use in 20 the manufacture of hosiery upon automatic knitting machines.

In the accompanying drawings Figure 1, represents, on a much exaggerated scale, a fabric made in accordance with my invention and in which the change is from 25 web having the greater number of wales to web having the lesser number of wales; Fig. 2, is a similar view illustrating a web in which the disparity between the number of wales in the two webs is still greater; Fig. 3, is a view illustrating a fabric in which the web having 30 the greater number of wales is a two-and-one rib, and the web having the lesser number of wales is a one-and-one rib; Fig. 4, is a view representing a fabric in which the web having the greater number of wales is a two-and-two rib and that having the lesser number of 35 wales is a one-and-one rib; Figs. 5 and 6, represent webs in which the change is effected from web having the lesser number of wales to web having the greater number of wales; Figs. 7 to 16 are diagrams showing the relative arrangement of cylinder and dial needles in 40 machines for producing the different fabrics shown; Figs. 17 and 18, are sectional views illustrating sufficient of a knitting machine to show the method of transfer when a stitch is changed from a dial needle to a cylinder needle; Figs. 19 and 20, are similar views illustrating the method of transferring from a cylinder needle to a dial needle; and Fig. 21, is an exaggerated view showing the tubular fabric as it appears upon the needles of the machine at the time that the change from one character of web to the other is being effected.

50 In Fig. 1, of the drawing, *a* represent plain stitch wales or those formed upon the cylinder needles of the machine, and *b* represent rib stitch wales or those

formed upon the dial needles of the machine, the web in courses 1 and 2 representing a one-and-one rib having a certain number of wales, say 160, in a tube of given 55 diameter, and the web in courses 4 and 5 representing a one-and-one rib having a lesser number of wales, say 120, the change being effected by interknitting in course 3, stitches of certain plain stitch wales, *a'* with adjoining rib wales *b* and in course 2 by transforming 60 the rib wale *b'* into a plain stitch wale *d*.

The arrangement of needles for knitting this fabric may be similar to that shown in Figs. 7 and 8, in which *x* represent cylinder needles which are always in action, *x'* represent cylinder needles from which stitches 65 are transferred onto adjoining dial needles, *w* represent cylinder needles which are inoperative during the production of the web containing the greater number of wales but receive stitches from corresponding dial needles before commencing the production of web 70 having the lesser number of wales, *y* represent dial needles which are always in action, *y'* represent dial needles from which stitches are transferred onto previously 75 inoperative cylinder needles *w*, and *y''* represent dial needles which receive stitches from the adjoining cylinder needles *x'*. This fabric is, therefore, composed in part of plain wales, in part of rib wales, in part of composite wales in which rib wales are transformed 80 into plain wales by direct transfer of stitches from dial to cylinder needles, and in part of the rib wales which have adjoining plain wales interknitted with or merged into them.

The fabric has what is termed a thirty-three-and-one-third (33 $\frac{1}{3}$) per cent' doubling, that is to say, the web having the greater number of wales has thirty-three-and-one-third (33 $\frac{1}{3}$) per cent. more wales than the web 85 having the lesser number of wales.

In Fig. 2, I have shown a fabric in which a fifty (50) per cent. doubling has been effected; *a* and *b* in this case representing respectively plain wales and rib 90 wales which continue as such throughout the fabric, *a'* representing a plain wale which is interknitted with an adjoining rib wale and *b'* representing a rib wale which is interknitted with the adjoining plain wale.

The arrangement of needles for producing this fabric 95 is shown in Figs. 9 and 10, *x* representing continuously acting cylinder needles, *y* representing continuously acting dial needles, *x'* representing cylinder needles from which stitches are transferred, *x''* representing cylinder needles onto which stitches are transferred, 100 *y'* representing dial needles which receive stitches from the needles *x'* and *y''* representing dial needles from which stitches are transferred onto the cylinder needles *x''*.

The fabric shown in Fig. 3, has, in courses 1 and 2, a web consisting of a two-and-one rib, that is to say, one having pairs of plain wales alternating with single rib wales, while the web shown in courses 4 and 5, is a one-and-one rib, change being effected in course 3 by transferring stitches of plain wales a' to adjoining rib wales b .

The arrangement of needles for effecting the production of this fabric is shown in Figs. 11 and 12, x representing the cylinder needles which are always in action, y representing the dial needles which are always in action, and x' representing the cylinder needles whose stitches are transferred to the adjoining dial needles in effecting the change in the character of the web.

15 In Fig. 4, I have shown a fabric in which there is a two-and-two rib in one portion and a one-and-one rib in the other portion, courses 1 and 2, showing the two-and-two rib, courses 4 and 5 showing the one-and-one rib, and course 3 representing the change course, the 20 change in this case being effected by interknitting stitches of plain wales a' with adjoining rib wales b , and stitches of rib wales b^2 with adjoining plain wales a .

The relative arrangement of cylinder and dial needles for producing a fabric of this character is shown in 25 Figs. 13 and 14, in which x represents the cylinder needles which are always in action, y represent the dial needles which are always in action, x' represent the cylinder needles which transfer their stitches to adjoining dial needles y and y' represent the dial needles which 30 transfer their stitches to adjoining cylinder needles.

In all of the fabrics thus far described, the change is effected from a web having the greater number of wales to a web having the lesser number of wales, but a reverse operation may be resorted to in accordance with 35 my invention. Thus in Fig. 5, I have shown a fabric in which a one-and-one rib web is changed to a two-and-one rib web, a representing the continuous plain wales and b the continuous rib wales, while c represent plain wales which, in course 3, are introduced between the adjoining plain and rib wales, the first 40 stitches of each of said introduced plain wales engaging with a stitch in course 1 of the adjoining rib wale.

In the arrangement of needles for producing this fabric, shown in Figs. 15 and 16, x represent the continuously acting cylinder needles, y the continuously acting dial needles, and x' the introduced cylinder needles, the object of interknitting the first course of each additional plain wale with a precedently formed stitch of the rib wale being to prevent the formation of 45 an eyelet hole at the point of introduction of the additional plain wale.

In Fig. 6, a similar fabric is shown, in which, however, the first stitch of each plain wale introduced in course 3 is caused to engage with a stitch in course 2, 50 of the adjoining rib wale, this effect being produced by causing the cylinder needle to engage with the stitch on the dial needle instead of with a precedently formed stitch.

In Figs. 7, 9, 11, 13 and 16, the dotted lines represent 55 the order of succession of the needles to which the knitting yarn is fed in producing the webs having the greater number of wales, and in Figs. 8, 10, 12, 14 and 15, the dotted lines represent the like order in producing the webs having the lesser number of wales.

60 In carrying out my invention, various forms of ma-

chine may be employed, but in Figs. 17 and 18, I have shown sufficient of the elements of one form of machine which has proven effective in practice to impart a proper understanding of the manner of manipulating the needles to effect the transfer of stitches from one to another. In these views 10 represents part of a needle cylinder, and 11 part of the dial, on the inside of the cylinder. The dial needles are carried by the lower ends of jacks 12, pivotally mounted upon a fixed ring 13, and having their upper ends acted upon by cams 70 upon a cam plate 14, this plate having two sets of cams; one for acting upon the jacks so as to cause operation of the dial needles for ordinary knitting, and another set for causing abnormal projection of the dial needles, so as to carry them outwardly beyond the cylinder 80 needles. This has the effect of drawing or stretching the webs so as to dispose the stitches of the same over the cylinder, as shown in Fig. 17, hence cylinder needles may be projected and caused to enter said stitches, as also shown in said Fig. 17, the dial needles from which 85 stitches are to be transferred directly to the naked cylinder needles w preserving their normal position above said needles w while being thus projected, but the dial needles which have to double their stitches with those of the cylinder needles being shogged or 90 moved laterally into line with the cylinder needles which are to receive such stitches, the projection of the dial needles being such as either to bring the stitches upon them, or precedently formed stitches, above the cylinder needles which are to engage the 95 same.

When the cylinder needles are projected so as to enter the stitches upon the dial needles, either of said needles may be moved laterally to the extent necessary to cause engagement of the cylinder needles with the dial 100 stitches, and the dial needles can then be withdrawn so as to cast their stitches onto the cylinder needles, as shown in Fig. 18, but when the cylinder needles engage stitches other than those upon the dial needles, the lateral movement referred to will not be necessary. 105

When a transfer is to be effected from a cylinder needle to a dial needle, said cylinder needles are in like manner abnormally projected, so that lugs or projections such as w' upon them may stretch the cylinder 110 stitches so as to draw them, or precedently formed cylinder stitches, into line with the dial needles, the latter being, if necessary, shogged or moved laterally into line with the cylinder needles from which the transfer is to be effected. 115

The operation of transferring from a cylinder needle to a dial needle is represented in Figs. 19 and 20.

My improved fabric can be knitted without arresting the operation of the machine and by the use of a continuous yarn it being understood that the knitting cams and the transfer cams are disposed at points so remote from each other that the knitting operation can be going forward upon certain of the needles of the machine while stitches are being transferred from or to other needles of the machine at a point more or less remote from the knitting point, thus in Fig. 21, X represents the knitting point and Y the transfer point at 120 which point is shown the beginning of the operation of transferring stitches from dial needles y' onto cylinder needles w .

The term "continuous" does not necessarily imply 135

unbroken continuity of a single yarn, but merely a continuous feed of yarn to needles of one and the same machine.

Having thus described my invention, I claim and desire to secure by Letters Patent:—

1. A machine-knit ribbed fabric comprising two webs, one having wales in excess of those in the other, some of the wales of each face extending throughout both webs, and other wales of each face being interknitted with wales of the other face at the point of change. 45
2. A machine-knit ribbed fabric comprising two webs, one having wales in excess of those in the other, some of the wales of each face extending throughout both webs, and other wales of either face having stitches drawn only through wales of the other face at the point of change. 50
3. A machine-knit ribbed fabric comprising two webs, one having wales in excess of those in the other, some of the wales of each face extending throughout both webs and 55 stitches of wales of each face being drawn through a single stitch of a preceding course at the point of change.
4. A seamless, tubular, machine-knit ribbed fabric comprising two webs, one having wales in excess of those in the other, some of the wales of each face extending throughout both webs, and other wales of either face having stitches drawn only through wales of the other face at the point of change. 60
5. A seamless, tubular, machine-knit ribbed fabric comprising two webs, one having wales in excess of those in the other, some of the wales of each face extending throughout both webs, and other wales of either face having stitches drawn only through wales of the other face at the point of change. 65
6. A seamless, tubular, machine-knit ribbed fabric comprising two webs, one having wales in excess of those in the other, some of the wales of each face extending throughout both webs, and other wales of either face having stitches drawn only through wales of the other face at the point of change. 70
7. A machine-knit ribbed fabric comprising two webs, and having a yarn common to both, one of the webs having wales in excess of those in the other, some of the wales of each face extending throughout both webs, and other wales of either face being interknitted with wales of the other face at the point of change. 75

wales in excess of those in the other, some of the wales of each face extending throughout both webs, and other wales of each face being interknitted with wales of the other face at the point of change.

8. A machine-knit ribbed fabric comprising two webs, and having a yarn common to both, one of the webs having wales in excess of those in the other, some of the wales of each face extending throughout both webs, and other wales of either face having stitches drawn only through wales of the other face where the change of web is effected.

9. A machine-knit ribbed fabric comprising two webs, and having a yarn common to both, one of the webs having wales in excess of those in the other, some of the wales of each face extending throughout both webs and stitches of wales of each face being drawn through a single stitch of a preceding course at the point of change.

10. A seamless, tubular, machine-knit ribbed fabric comprising two webs having a yarn common to both, one of the webs having wales in excess of those in the other, some of the wales of each face extending throughout both webs, and other wales of each face being interknitted with wales of the other face at the point of change. 60

11. A seamless, tubular, machine-knit ribbed fabric comprising two webs having a yarn common to both, one of the webs having wales in excess of those in the other, some of the wales of each face extending throughout both webs, and other wales of either face having stitches drawn only through wales of the other face where the change of web is effected. 65

12. A seamless, tubular, machine-knit ribbed fabric comprising two webs having a yarn common to both, one of the webs having wales in excess of those in the other, some of the wales of each face extending throughout both webs and stitches of wales of each face being drawn through a single stitch of a preceding course at the point of change. 70

In testimony whereof, I have signed my name to this specification, in the presence of two subscribing witnesses.

ROBERT W. SCOTT.
